UNITED STATES PATENT OFFICE.

EDWIN B. STIMPSON, OF BROOKLYN, NEW YORK.

SOLE-EDGE-FINISHING TOOL.

SPECIFICATION forming part of Letters Patent No. 270,148, dated January 2, 1883.

Application filed October 13, 1882. (No model.)

To all whom it may concern:

Be it known that I, EDWIN B. STIMPSON, of the city of Brooklyn, in the county of Kings and State of New York, have invented a new and useful Improvement in Edge-Finishing Tools for Shoe-Makers, of which the following is a specification.

My invention relates to that class of edge-finishing tool which comprises a stock, a handle to which the stock is secured, and a piece adjustable in the stock and adapted to be secured in different positions therein to form a fore-part tool for different thicknesses of soles.

The invention consists in novel details of construction and combinations of parts illustrated in the accompanying drawings, and pointed out in the claims.

In the drawings, Figure 1 represents a side view of my improved tool. Fig. 2 represents a sectional view thereof, and Fig. 3 represents a side view of the round piece removed from the stock.

Similar letters of reference designate corresponding parts in all the figures.

A designates the stock, one edge or face, a, of which is smooth and adapted to serve as a heel-burnisher, and at the ends of the face which forms the heel-burnisher are formations b or grooves of peculiar shape, which adapt the tool for use in finishing the shanks of boots and shoes and take the place of two shank-irons.

Through the stock A is formed a hole, c, and in said hole is fitted a round piece, B, of steel, which is adapted to be turned freely in the stock without removing it therefrom, and also adjusted lengthwise therein, so that its ends will project more or less therefrom. This round piece has at one end a lip or flange, d, which is formed integral with it, and at the other end it may have a similar lip or flange, d'. In the latter case the last-mentioned lip or flange should be capable of removal to enable the round piece to be inserted into and withdrawn from the stock when desirable. As hereshown, the lip or flange d' is formed integral with a screw, d², which enters a tapped hole, d³, in the end of the round piece, as shown in Fig. 2.

C designates the handle of the tool, which has extending through it a rod, C', secured therein by a nut, e. At the end of the rod C'

is formed a screw, f, which screws into a tapped hole, f', in the stock A, and is adapted to impinge against the round piece B, and thereby retain it in place. In the round piece B are formed four recesses or cavities, g, three of which are shown in Fig. 3, and into which the conical end of the screw f may enter, as shown in Fig. 2. By means of these recesses or cavities g the projection of the ends of the round piece B from the stock are definitely fixed. For example, when the round piece is secured in the position shown in Fig. 2 one end projects farther from the stock than the other end, and adapts the tool for two thicknesses of sole. 65 By turning the piece one-quarter of a turn and again tightening the screw f the tool is adapted for two other thicknesses of sole, and so on until the piece B has been turned entirely round. It will therefore be seen that by turning and 70 adjusting the round piece B lengthwise I adapt the tool for eight thicknesses of sole and dispense with the separate fore-part tools commonly employed.

In the round piece B are filed small grooves 75 h, which are so placed that when the round piece is secured by the screw f entering any one of the recesses g the grooves h on the opposite side of the piece B will be flush with the projections i on the opposite faces of the 80 stock, as shown in Fig. 2. These small grooves form what is known as the "crease" at or near the lower edge of the sole.

The flanges or lips d d' have notches j in their edges, by which they are divided into 85 four equal parts, and each part is adapted to form a guard and set round the stitch or upper edge of the fore part.

Close to each lip or flange is the usual fillet, k, which forms the ordinary rabbet-like crease 90 on the upper edge of the fore part.

By removing the lip or flange d' the piece B may be taken out and another piece having its recesses g and grooves h so placed as to adapt it for ladies' shoes may be inserted.

Instead of the piece B being adapted for eight thicknesses of fore part, it might be adapted for ten or more thicknesses by dividing its circumference into five or more parts, or for only six thicknesses by dividing its circumferences into only three parts.

The round piece B might have a lip or flange

on one end only, in which case it would not be adapted for so many different thicknesses of fore part.

If desirable, the tool might be used only for a fore-part iron for different thicknesses of sole, and in such case the stock A would not be provided with the heel-burnisher *a* and shank formations *b*.

What I claim as my invention, and desire to secure by Letters Patent, is—

1. The combination of the stock A, the round piece B, capable of being turned in the stock without being removed from the stock, and having the lip or flange at one or both ends,

and the recesses *g*, and the handle C, and its screw *f*, which serves as a means of attaching the handle to the stock and for securing the round piece in place in the stock, substantially as herein described.

2. The combination of the stock A, the piece B, provided with the lips or flanges *d d'*, having notches *j*, and also provided with the recesses *g* and grooves *h*, and the handle C, with its screw *f*, substantially as described.

EDWIN B. STIMPSON.
